UNITED STATES PATENT OFFICE.

JOHN LOGAN, OF CHICAGO, ILLINOIS.

COMPOSITE ROOFING.

Application filed March 13, 1922. Serial No. 543,222.

To all whom it may concern:

Be it known that JOHN LOGAN, a citizen of the United States, and a resident of the city of Chicago, county of Cook, State of Illinois, has invented an Improvement in Composite Roofing, of which the following is a specification.

This invention relates to composite roofing and, among other objects, is intended to provide an improved roofing material which is pleasing in appearance, durable and relatively inexpensive to manufacture.

One embodiment of the invention is illustrated in the accompanying drawings in which

Fig. 1 is a perspective view of a roofing strip illustrating one application of the invention, and having certain portions broken away to show more clearly the construction.

Fig. 2 is an enlarged cross-sectional view taken along the line 2—2 of Fig. 1.

Fig. 3 is a fragmentary sectional view considerably enlarged illustrating more clearly a feature of the invention.

Fig. 4 is a view of a portion of a roof showing the effect produced by applying thereto strips of roofing embodying features specifically illustrated in Fig. 3.

Referring to the drawings, the composite roofing forming the subject matter of this invention includes a relatively inexpensive sheet of fibrous material 5 such as rag felt or the like, which constitutes the foundation or body portion of the roofing.

The sheet 5 may be impregnated with a suitable preserving compound such as light asphalt, that is, an asphalt having a low melting point. This tends to resist the penetration of moisture into the felt and thereby prevent the deterioration thereof.

One or both faces of the felt may be covered with a relatively thick coating or layers 6, 6 of impervious protecting compound, such as heavy asphalt or the like.

These layers besides preventing the penetration of moisture into the fibrous sheet, whether the latter be wholly impregnated or dry, also tend to stiffen and strengthen the sheet and to become a substantial part of the body of the roofing.

One of the layers 6 has applied thereto a relatively thin sheet of metal veneer or surfacing material 7, such as copper or other material not susceptible to atmospheric conditions.

The said veneer or surfacing material is

applied, preferably, to that portion of the roofing ordinarily exposed when the same is on a roof or the like, and is intended to protect the roofing from sparks, fire-brands and the like, as well as to lend stability and weather resisting qualities to the roofing.

The sheet 7 may be provided with a series of perforations 8 which may be arranged in straight parallel lines extending transversely of the sheet, as shown, or may be arranged in any other designs to produce the desired effect when the strip is laid on a roof or the like.

The metal sheet may be imbedded in the adjacent layer of protecting compound a distance substantially equal to the thickness of the veneer, thereby bringing its upper surface substantially flush with the uncovered surface of the layer and, if the sheet be perforated, causing the compound to be pressed into the perforations in a manner to be exposed at the outer surface of the sheet.

The entrance of the compound into the perforations not only assist the adhesive qualities of the compound by anchoring the veneer securely thereto, but the exposure of the compound through the perforations, which are of greater lineal dimension than the narrow intermediate connecting strips 9, presents the appearance of a continuous line, suggestive of the space between adjacent edges of ordinary shingles, as shown in Fig. 4, when the overlapping strips are laid on a roof or the like.

If desired the compound may be pressed through the perforations and beyond the outer surface of the sheet 7, where it may be pressed or permitted to cover the connecting strips 9, thereby actually forming a continuous line of compound at the surface of said sheet.

Obviously, the roofing embodying this invention may be made in long sheets to be handled in rolls as in the case of some prepared roofing at present in use or may be cut to form individual shingles, or may be cut into shingle strips of any desired design.

Composite roofing constructed in accordance with this invention possesses distinct advantages over all-metal roofing, in that it is cheaper, provides a better insulation for heat and cold, deadens the noise of rain and hail, is more water-proof and does not require prepared roofing underneath; and is superior to ordinary asphalt roofing in that it provides better fire protection, is lighter

in weight and presents a more pleasing appearance when exposure to the weather has caused the metal to assume its natural colorings.

5. In other words, it possesses all the advantages and eliminates the disadvantages of the ordinary asphalt roofing and the all-metal roofing.

If desired, the metal sheet 7 may be corrugated, crimped or embossed with various ornamental designs, or may be oxidized or otherwise treated to produce the desired appearance.

Obviously, the invention is not limited to the particular construction shown, but may be variously modified. Moreover, it is not indispensable that all the features of the invention be used conjointly as they may be used to advantage in variously different 20 combinations and sub-combinations.

Having thus described my invention, I claim:

1. Roofing material comprising, in combination, a sheet of felt, or the like, impregnated with light asphalt; a layer of heavy asphalt on each side of said felt; and a relatively thin sheet of copper veneer covering a portion of one of said layers and imbedded therein a distance substantially 25 equal to the thickness of said veneer.

2. Roofing material comprising, in combination, a sheet of impregnated felt; layers of impervious protecting compound covering opposite sides thereof; and a metal 35 sheet covering a portion of one of said layers and imbedded therein.

3. Roofing material comprising, in combination, a sheet of impregnated felt; lay-

ers of impervious protecting compound covering opposite sides thereof; and a perforated metal sheet covering a portion of one of said layers and imbedded therein.

4. Roofing material comprising, in combination, a sheet of impregnated fibrous material; layers of impervious protecting compound on opposite faces thereof; and a metallic sheet adjacent one of said layers, the said metallic sheet having perforations for exposing some of the compound therethrough.

5. Roofing material comprising, in combination, a sheet of material coated with a layer of heavy asphalt or the like and having the portion thereof, intended to be exposed, covered with a thin copper sheet provided with a series of perforations for receiving therein some of the said asphalt.

6. Roofing material comprising, in combination, a fibrous body layer, a metal surface layer having perforations therein, and an adhesive between the two.

7. Composite roofing comprising, in combination, a sheet of material coated with heavy asphalt; a surface sheet of thin material united therewith; and means associated with said surface sheet whereby designs are formed of said asphalt on said roofing.

8. Roofing material comprising, in combination, a sheet of flexible material coated with heavy asphalt; and a thin metallic sheet united therewith and having perforations adapted to form stencil-like designs by exposing the asphalt therethrough.

In testimony whereof, I have signed my name to this specification.

JOHN LOGAN.
